DESIGN FOR A LUMINAIR

Joseph W. Gosling, Schenectady, N. Y., assignor
to General Electric Company, a corporation of
New York

Application October 16, 1936, Serial No. 65,321

Term of patent 14 years

To all whom it may concern:

Be it known that I, Joseph W. Gosling, a citizen
of the United States, residing in Schenectady,
county of Schenectady, State of New York, have
invented a new, original, and ornamental Design
for a Luminair, of which the following is a speci-
fication, reference being had to the accompan-
ying drawing, forming a part thereof.

Fig. 1 is a front perspective view of the lumi-
nair, showing my new design; and

Fig. 2 is a fragmentary top perspective view of
the upper portion thereof.

I claim:

The ornamental design for a luminair, as
shown.

JOSEPH W. GOSLING.
